UNITED STATES PATENT OFFICE.

OTHO M. OTTE, OF JAMESTOWN, NEW YORK.

FOLDING TABLE.

1,300,861.

Specification of Letters Patent. Patented Apr. 15, 1919.

Application filed August 17, 1918. Serial No. 250,302.

To all whom it may concern:

Be it known that I, OTHO M. OTTE, citizen of the United States, residing at the city of Jamestown, in the county of Chautauqua and State of New York, have invented certain new and useful Improvements in Folding Tables, of which the following, taken in connection with the accompanying drawings, is a specification.

10 The invention relates to folding tables; and the improvement consists in providing a simple top or tray, suitable for hospital and similar uses, with bent spring rod legs which are hinged to the under side of said top or tray by means of holding clips or hinging bracket pieces which are so shaped as to receive said spring legs into and out of hinging and latching engagement both for attachment and removal of said legs and 15 for holding said legs in the set-up and folding positions, the integral resilience of said legs providing the expanding or contracting holding force within said hinging and latching clips or brackets; and the invention consists in the novel features and combinations 20 hereinafter set forth and claimed.

In the drawings, Figure 1 is a perspective view of the table in the set-up position showing the preferred form of top or tray and 25 of the spring legs. Fig. 2 is a perspective view of the under side of the folding table showing the simple form of latching and hinging brackets at one end and the more elaborate and stronger form of brackets at 30 the other, with the folding legs supported in different positions by said brackets. Fig. 3 is a perspective view of a front corner of the top showing the tubular end of the front roll with the round headed closure plug therein. 35 Fig. 4 is a perspective view of one of the preferred forms of spring legs removed from the hinging brackets on the table top. Fig. 5 is an edgewise elevation of one of the simple or skeleton forms of hinging clips which 40 is attached to the under side of the top or tray preferably by spot welding, and showing the end of the leg in the folded position, the remainder of the leg being broken away and the set-up position shown in dotted line. 45 Fig. 6 is a plan view of the oppositely placed hinging clips or brackets on the under side of the top, with portions of the spring leg in dotted and solid outline to show the movement of the same from the set up to the 50 folded position. Fig. 7 shows a perspective view of the simple or skeleton form of one

of the locking and hinging clips or brackets; and Fig. 8 is a perspective view of the inner portion of one of said holding clips showing the upturned locking point and latch for the spring leg; and Fig. 9 is a perspective view of a slight change of the simpler form of hinging and locking bracket for the spring legs which gives a larger and stronger welding attachment to the top.

Like characters of reference refer to corresponding parts in the several views.

The numeral 10 designates the top or tray which is preferably made of sheet metal of sufficient weight and in the tray or guarded form so that it may be enameled, preferably with hard or vitreous coatings to render the same hygienic. One of the simple forms of said top is shown having an upwardly extending guard rail 11 around three sides and a downwardly extending cylindrical roll 12 across the open front edge of the same. The roll 12 has a round headed closure plug 13 in each end to finish the same.

The top 10 is usually provided with four 80 legs 14 which are bent in any desired design from a metallic rod, preferably of spring metal, so that the leg 14 will of its own resilience spring into and out of suitable holding clips or hinge brackets. These 85 holding clips may be arranged so as to hold the legs 14 rigidly yet removably in the set-up position. The legs 14 are preferably made in the U-shape with oppositely turned ends 15 so as to engage beneath said holding 90 brackets. They would serve a good purpose in thus being made removable without hinging to fold the same but are preferably made foldable so that all that is necessary to fold the same from the set-up position is to compress or expand the two arms of the 95 preferably U-shaped leg thereby releasing said spring legs from the holding notches and permitting the folding of the leg against the underside of the top 10, the spring of the 100 leg holding the same in both the folded and set up positions.

In order to so hinge the upper ends 15 of the leg 14 they are preferably turned outward as shown in Fig. 4 so that the two portions of the spring leg will lock between holding clips or brackets 16 and 17 which are shaped nearly alike except that they are rights and lefts, there only being a slight difference in the shape of the latching projection so as to better control the spring legs in springing them into holding engagement.

with the clips or hinging brackets 16 and 17 in turning from the folded to the set up position.

Each of the clips 16 and 17 in their simple form as provided for the lighter tables are provided with a raised portion 18, and open ended slot 19 extending up into the raised portion 18 sufficiently to permit the angular leg end 15 of the leg 14 to extend into the slot 19 from the inner side. The side 20 of the raised portion 18 is made at an inclined angle so that when the spring leg 14 is turned to the folded position it will lockingly hold in said folded position beneath the incline 20 of the clips 16 and 17. The slot 19 permits the end 15 to hingingly spring thereinto so that it may be turned from the folded to the set up positions or the reverse, a preferably V-shaped notch 21 being provided in the raised portion 18 at one side into which the leg 14 springs and resiliently holds one arm of said leg 14, the other arm being held in the similar notch 21 in the opposite clip; thus the two clips 16 and 17 firmly hold the resilient leg 14 in either the folded or set up position. The projections 22 and 23 are made slightly different on clips 16 and 17, the projection 22 not being used as the riding or leading edge for the leg 14 on that side, while the projection 23 is more rounded and the outer edge is flanged upward slightly so as to form a convenient surface for leading the spring arm of the leg into the notch 21, thus when the leg 14 is raised from the folded position the arm of said leg which engages in the notch 21 in the clip 16 is first inserted and the opposite arm naturally follows as it is pressed around the turned up or cam shaped point 23. Both the clips 16 and 17 are attached to the under side of the top preferably by spot welding through the attaching lugs 24.

A slight change of the simpler form of clip shown in Figs. 6-8 is shown in Fig. 9, in which the slot 19 and notch 21 with latching projection is made substantially the same. The attaching or welding part of the clip or bracket is closed and braced to give a larger welding surface which is particularly useful in large tables where strongly attached clips are used.

The lower ends or feet 30 of the legs 14 are preferably turned to one side to both give a larger and firmer supporting surface

and provide a sidewise hand grip for operating and controlling said legs in raising them from the folding position against the underside of the top 10 or replacing them in said folded position.

I claim as new:

1. In a folding table, a top, legs for the top having out-turned inner ends, and sheet metal clips for each leg having attaching portions and having the part between its ends extended inwardly on one side at an incline, then approximately parallel to the attaching portions and connected at its opposite side to the adjacent attaching portions, the last named side being cut-away to leave the adjacent edge of the parallel part exposed, said edge being cut-away to form a socket for receiving the side of the leg, the inclined side being also cut-away to receive the out-turned end of the leg.

2. In a folding table, a top, resilient legs having substantially right angular ends, and sheet metal clips each having a pair of spaced attaching lugs at one end and a body having an inclined part extending inwardly from the inner ends of the lugs, said inclined part having an aperture aligned with the space between the lugs and being extended outwardly and approximately parallel to the top and having a free edge formed with a notch, said apertures and the spaces between the lugs being formed to receive the right angular ends of the legs and the notches being formed to have the leg sides snap thereinto.

3. In a folding table, a top, resilient legs having substantially right angular ends, and sheet metal clips each having a pair of spaced attaching portions and a bowed portion which latter is connected on one side to the inner end of each of said attaching portion and has an aperture on said side registering with the space between the attaching portions to receive the right angular leg ends and having the opposite side of its bowed portion formed with a free edge provided with a notch to receive the side of the leg.

In testimony whereof I have affixed my signature in the presence of two witnesses.

OTHO M. OTTE.
